UNITED STATES PATENT OFFICE

2,302,034

COAL MINING MACHINE

Joseph F. Joy, Franklin, Pa., assignor to Sullivan Machinery Company, a corporation of Massachusetts

Application November 24, 1939, Serial No. 305,863

1 Claim. (Cl. 262—28)

This invention relates to mining machines, and more particularly to an improved safety mechanism for a coal mining machine of the flexibly fed, floor cutter type adapted to operate on a steeply inclined or pitching coal seam.

During cutting of coal in accordance with the longwall system, on a steeply inclined or pitching coal seam, the feed cable of the machine feeding means is usually anchored at the top of the pitch so that as the feed cable is wound in by its feed drum, the machine is fed upwardly along the coal face to make a cut in the coal. Unless some safety measure is taken, there is inherent danger, due to the possibilities of feed cable breakage or release of the feed cable from its anchor, of accidental sliding of the comparatively heavy machine rapidly down the pitch with the possibility of injury to the operator and damage to the machine. To eliminate this possibility of the machine accidentally moving without control down the pitch, safety mechanism is usually provided so that in the event the feed cable breaks or releases from its anchor, or the feeding mechanism otherwise fails to function, the safety mechanism will act automatically to prevent undesired sliding of the machine down the pitch. Such safety mechanism usually comprises a safety drum on the machine rotatable at the same speed as the feed drum and having its cable attached to an anchor at the top of the pitch so that if the feed cable breaks or releases from its anchor, the safety cable will automatically hold the machine against undesired movement down the pitch. Such safety drums usually have some form of means for effecting rotation thereof in cable winding direction and means for precluding automatically rotation thereof in unwinding direction. Also a brake device is usually associated with the safety drum so that the latter may rotate in cable unwinding direction under frictional control at the operator's will, thereby to enable lowering of the machine down the pitch under the control of the safety cable. Due to the fact that such known types of safety mechanism were positively driven at the same winding speed as the feed drum, the safety cable usually had to be slack, and so, in the event the feed cable failed to function and the machine started to slide down the pitch, the safety cable would frequently break or become released from its anchor, when the weight of the machine was suddenly taken thereby.

An object of this invention is to provide an improved safety mechanism for a coal mining machine whereby the possibility of undesired

movement of the machine down the pitching seam is prevented, the improved safety mechanism embodying features which overcome certain disadvantages of previous known devices. 5 Another object is to provide an improved safety mechanism for a coal mining machine embodying a safety drum mounted on the mining machine and having wound thereon a safety cable, the drum having improved driving and controlling means therefor whereby the safety cable is always automatically maintained taut as the machine is fed upwardly along the coal face. A further object is to provide an improved driving means for the safety drum embodying frictional means whereby the safety drum at least tends to wind in its cable at a rate slightly faster than the cable winding rate of the feed drum of the machine, whereby the safety cable is always automatically maintained under the desired tension, the frictional means automatically slipping when the safety cable becomes taut. These and other objects and advantages of the invention will, however, hereinafter more fully appear.

In the accompanying drawings there is shown for purposes of illustration one form which the invention may assume in practice.

In these drawings:

Fig. 1 is a plan view of a coal mining machine with which an illustrative embodiment of the invention is associated.

Fig. 2 is a side elevational view of a mining machine shown in Fig. 1.

Fig. 3 is a detail view illustrating the safety drum ratchet.

Fig. 4 is an enlarged horizontal sectional view, with parts shown in plan, taken substantially on line 4—4 of Fig. 2.

Fig. 5 is a view in longitudinal vertical section taken substantially on line 5—5 of Fig. 4.

Fig. 6 is a detail view of a portion of the drum driving mechanism.

In this illustrative embodiment of the invention the improved safety mechanism, generally designated 1, is shown associated with a coal mining machine generally designated 2. The mining machine disclosed herein is of the flexibly fed, longwall floor cutter type, although it will be evident that the improved safety mechanism may be associated with coal mining machines of various other types.

The coal mining machine disclosed herein may be of the same general character as that disclosed in the patent to Morris P. Holmes, No. 1,968,769, patented July 31, 1934, while the safety mechanism disclosed herein is an improvement

over that disclosed in the patent to Morris P. Holmes, No. 2,053,288, patented Sept. 8, 1936.

The mining machine comprises a low compact machine frame 3 having a plane bottom surface 4 adapted to rest upon and slide in any direction over the mine floor. The machine frame comprises a central motor frame section 5, a rear cutter carrying frame section 6 and a front feed frame section 7, the motor frame section being arranged between the cutter and feed frame sections, and these sections being suitably rigidly united. Pivotally mounted at 8 on the cutter frame section 6 at the rear end of the machine frame for horizontal swinging movement relative thereto, is an elongated horizontal plane cutter bar 9 having guided for circulation about its margin an endless cutter bit carrying cutter chain 10, the cutter bar being swingable horizontally about its pivot into right angle positions at either side of the machine frame or into a position extending lengthwise of the machine frame, as shown in full and dotted lines in Fig. 1. Mounted on the cutter bar is a usual locking element 11 for locking the cutter bar in its different positions about its pivot relative to the machine frame. Carried by the feed frame section is a horizontal feed drum 12 arranged for rotation about a vertical axis located in the central longitudinal vertical plane of the machine and having wound thereon a usual feed cable 13. Arranged at opposite sides of the feed drum are sets of horizontal guide sheaves 14 for guiding the feed cable relative to the feed drum during the various operations of the machine. The free end of the feed cable is attachable to the locking pin 11, and when the locking pin is released the feed cable may be wound in by its drum to effect swinging of the cutter bar about its pivot. To effect feeding of the machine along the coal face during the cutting operation, the feed cable is extended from its drum in the manner indicated in full lines in Fig. 1, and is connected at its free end to a suitable anchor located in advance of the machine adjacent the coal face, and as the feed cable is wound in, the machine is fed bodily over the mine floor in a manner well understood in the art. Arranged within the central motor frame section 5 is a reversible motor for driving the cutter chain 10 and feed drum 12 in either of opposite directions in accordance with the direction of cutting. When it is desired to reverse the direction of cutting of the machine, the cutter bits of the cutter chain 10 are, of course, reversed within their respective chain blocks and the feed cable is rewound on the feed drum.

Now referring to the driving connections between the motor and the feed drum, it will be noted that fixed to the motor power shaft 15 is a spur motor pinion 16 (see Fig. 4) meshing with a spur gear 17 which in turn drives a longitudinal shaft 18. Fixed to and driven by the shaft 18 is a spur gear 19 meshing with a spur gear 20 having its hub keyed to a horizontal longitudinally extending shaft 21. Secured to the forward end of the shaft 21 is a spur gear 22 meshing with a spur gear 23 keyed to a parallel shaft 24. Secured to and driven by the shaft 24 is a spur gear 25 meshing with a spur gear 26 arranged coaxially with the spur gear 20 and surrounding and journaled on the shaft 21. Journaled within bearings supported within the gears 20 and 26 and arranged coaxially with and surrounding the shaft 21 is a tubular shaft 27 having formed thereon a worm 28 meshing with a worm wheel 29. The gear train, including gears 16, 17, 19

and 20, constitutes a high speed drive, while these gears, and additionally, the reduction gears 22, 23, 25 and 26, constitute a low speed drive, and these drives are selectively connectable with the opposite ends of the worm shaft 27 through friction disc clutches 30 and 31 respectively.

The particular clutch mechanism and the actuating and controlling means therefor are similar in design to those described in the above mentioned Holmes Patent 1,968,769. Continuous high speed rotation of the worm shaft 27 is effected by direct connection of the worm shaft 27 with the high speed gear 20, while continuous rotation of the shaft at a low speed and intermittent rotation at a number of different still lower mean speeds are effected by the following mechanism. A clutch-applying element 32 reciprocably mounted on the worm shaft 27 is operative to transmit the pressure of a clutch shipper yoke 33 which is pivotally supported at 34, to effect loading of the high speed friction clutch 30, and thereby to effect connection between the high speed gear 20 and the worm shaft 27. A similar clutch-applying element 35 is arranged adjacent the opposite end of the worm shaft 27 and is movable by a clutch shipper yoke 36 pivotally mounted at 37 to effect loading of the low speed friction clutch 31 and thereby to effect connection of the low speed gear 26 to the worm shaft 27. Formed integral with the low speed gear 26 is a cam 38 (see also Fig. 6) with which engages a plunger 39 slidably guided in a bore 40. This plunger is pivotally connected at 41 with one end of a horizontally swingable lever 42 whose opposite end is pivotally connected at 43 to a member 44 secured to a rod 45. The outer end of this rod is provided with a cylindric enlargement 46 providing a shoulder 47, and a spring 48 is compressed between an abutment 49 on the rod and a washer 50 slidably mounted upon the rod and normally engaging the shoulder 47 under the influence of the spring. The cylindric enlargement 46 on the rod passes through a trunnion device 51 supported by the shipper yoke 36. It will be evident from the foregoing description that, if the lever 42 is fulcrumed at a properly located point, movement of the plunger 39 by the cam 38 to the right in Fig. 6 effects, through the lever 42, endwise movement of the rod 45 to the left as viewed in Fig. 4, and such movement of the rod, through the spring 48 and the washer 50, imparts a load to the shipper yoke 36. The load imparted will be determined by the extent of movement of the rod and the degree of compression of the spring, and these will depend upon the position of the fulcrum of the lever 42. A movable fulcrum for the lever 42 is provided by trunnion devices 52 which are held upon a longitudinally movable rod 53 between a collar 54 on the rod and the inner end 60 of a sleeve 55 which surrounds and is movable backwardly and forwardly with the rod. The opposite end of the rod 53 has secured thereto an abutment 56 which, on movement of the rod 53 to the right as viewed in Fig. 4, applies pressure to trunnion devices 57 surrounding the rod and pivotally mounted in the adjacent end of the shipper yoke 33. The rod 53 extends, as noted above, through the sleeve 55, and has formed thereon an abutment 58 engageable with a rotatable hand nut 59, the latter being rotatably mounted between the abutment 53 and the outer end of sleeve 55, on the rod in the manner shown, and threadedly engaged at 60 to a member 61 secured within the machine frame. Obviously, the collar 54 and abutment 58 hold the trunnion

devices 52, sleeve 55 and hand wheel nut 59 against longitudinal movement relative to the rod 53; and longitudinal movement in either direction of the rod, the trunnion devices 52 and the sleeve is effected by proper rotation of the hand wheel nut 59 relative to the threaded member 61. Rotation of the hand wheel nut 59 in a direction to cause movement of the rod 53 toward the right in Fig. 4 results in loading of the high speed friction clutch 30 and driving of the worm shaft 27 directly by the high speed gear 20, and the movement of the fulcrum of lever 42 which is also effected precludes loading of clutch 31 while high speed drive is taking place. Rotation of the hand wheel nut in a direction to effect movement of the rod 53 toward the left in Fig. 4 tends to move the lever 42 bodily towards the left, and causes the end of the lever 42 connected to plunger 39 to move the latter toward the left and thereby into engagement with the cam 38; and upon movement of the fulcrum sufficiently far to the left, the other end of the lever 42 will have sufficient throw so that the shoulder 47 will pass inside the trunnion devices 51 and permit the washer 50 to coact with the trunnion devices 52 to load the low speed friction clutch 31. Obviously, when the spring is under sufficient compression so that it will yield only when a pressure adequate to effect power transmission through the low speed friction clutch 31 is applied to the clutch-applying element 35, the proper leftward adjustment of the fulcrum devices 52 may effect rotation of the worm shaft 27 at a low speed by the low speed gear 26 for any desired part of each revolution of the latter. When the rod 53 is moved to the left so far that the washer 50 continuously presses under the pressure of the spring 48 against the trunnion devices 51, continuous rotation of the worm shaft 27 will take place, and the spring will compress during each rotation of the low speed gear 26 an amount substantially equal to the full throw of the cam; but since the load of the spring is desirably above the minimum necessary to effect power transmission through the friction clutch, there will be no release even when the lowest point in the cam is opposite the plunger. However, by moving the rod 53 graduated amounts toward the right in Fig. 4 from its extreme left position mentioned, the period of drive during each rotation of the gear 26 may be progressively reduced until it is entirely discontinued. It is accordingly evident that the worm shaft 27 may be driven continuously at a relatively high speed, continuously at a relatively low speed and intermittently at low speeds at any desired point between the maximum low speed and zero.

The driving connection between the worm wheel 28 and the feed drum 12 comprises a vertical shaft 65 to which the worm wheel is keyed, and rotatable with and driven by this shaft at the lower end thereof is a spur gear 66 meshing with the teeth of an internal gear 67 formed on the feed drum 12. From the foregoing, it is evident that the feed drum may be rotated in cable winding direction at a relatively high speed under the control of the friction clutch 30, at a relatively low speed under the control of the friction clutch 31 and at any desired speed between the maximum low speed and zero.

Now referring to the improved safety mechanism 1, it will be noted that formed integral with the top plate 68 of the feed frame section 1 is a stub shaft 69 arranged with its longitudinal axis vertical and lying in the same longitudinal

vertical plane as the axis of rotation of the feed drum 12, and this stub shaft supports bearings 70 on which is journaled the hub of a cylindric member 71. This cylindric member has formed thereon internal gear teeth 72 with which mesh the teeth of a spur gear 73 keyed to the upper end of the vertical shaft 65. Journaled on a bearing sleeve 74 supported by the cylindric member 71 is a safety drum 75 having wound thereon a safety cable 76. The safety drum 75 is arranged at the top of the machine frame in horizontal planes above the feed drum 12, in the manner shown. Formed integral with the hub of the cylindric member 71 is a sleeve-like portion 77 having keyed thereto a series of clutch discs 78 which are interleaved with a series of clutch discs 79 keyed to the hub 80 of the safety drum 75. Threaded at 81 within an opening formed axially within the stub shaft 69 is a screw 82 having formed integral therewith a hand wheel 83 herein disposed above the top of the safety drum. Connected by a semi-permanent clutch 84, having slidingly interlocked teeth, to the upper end of the stub shaft 69 is a cylindric member 85. This cylindric member 85 has an external circumferential annular groove receiving a sealing ring 86 which sealingly engages the walls of the bore in the hub 80 to prevent access of foreign matter to the internal structure and oil leakage. The cylindric member 85 is annularly grooved at 87 at its lower face, and extending upwardly from its groove are vertical recesses receiving a series of coiled springs 88. These springs act on the upper race of a ball-bearing clutch-applying element 89 so that at times the springs act to load the friction clutch 73, 79 through the element 89. The clutch connection 84 serves to hold the cylindric member 85 against rotation, and there is a limited sliding movement between the interlocking clutch teeth so that the cylindric member 85 may be moved slightly upwardly and downwardly, and the springs 88 urge the member 85 upwardly against the hub of the hand wheel 83. When the gear 73 is driven by the shaft 65 through the gearing above described in connection with the feed drum 12 and the hand wheel is rotated to move the screw 82 downwardly relative to the stub shaft 69, the springs 88 are compressed sufficiently to effect loading of the friction clutch discs, and as a result the safety drum 75 is rotated concurrently with the feed drum 12 in cable winding direction. Upon continued rotation of the hand wheel, the bottom of the annular groove 87 will come into contact with the upper ball race of the element 89, thereby positively to increase the loading of the friction clutch. Various means may be utilized to provide a slightly higher maximum winding speed for the drum 75, and herein the safety drum 75 is of a slightly larger diameter than the feed drum 12, and both drums are adapted to be driven concurrently by the shaft 65 through identical gearings, and accordingly the safety cable 76 will, barring clutch slippage, be wound in at a rate slightly faster than the feed cable. If desired the safety drum may be of the same diameter as the feed drum and the latter be driven at a slightly higher speed. Suitable vertical guides 90 having cable-receiving grooves are provided on the feed frame section for guiding the safety cable with respect to the safety drum.

Associated with the safety drum 75 is a ratchet mechanism comprising ratchet teeth 91 formed on the periphery of an annulus 92 secured, as by

riveting, to the lower flange of the safety drum. Engageable with the ratchet teeth is a double-ended reversible pawl 93 pivotally mounted at 94. Engageable with the pawl is a spring-pressed plunger 95 mounted in a shiftable member 96 pivotally mounted at 97 and having a handle 98 for swinging it. This pawl, by its engagement with the ratchet teeth, serves to prevent undesired rotation of the safety drum 75 in cable unwinding direction. Accordingly reliance need not be placed on the friction device 78, 79 to hold the machine weight if the feed cable breaks, and power consumption may be kept low by relatively light loading of the clutch discs mentioned. As are the cutter chain and feed drum, the safety drum 75 is reversible, and when the motor of the mining machine is reversed to effect cutting in the opposite direction, it is necessary to rewind the safety cable on the drum. By shifting the member 96, the pawl may be reversed whenever the safety drum is reversed and the drum may be freed for quick unwinding of the safety cable. In Fig. 1 the pawl is shown in its released position.

The general mode of operation of the mining machine will be clearly apparent from the description given. When it is desired to make a cut along a coal face of a steeply inclined or pitching coal seam, the machine is initially located with respect to the coal face at the bottom of the pitch. The locking pin 11 is then released, and the feed cable 13 is attached to the locking pin, and as the feed cable is wound in by its drum the cutter bar 9 is swung horizontally about its pivot to effect a sumping cut beneath the coal. Thereafter, the feed cable is detached from the locking pin and the latter is operated to lock the cutter bar to the machine frame. The feed cable is then extended forwardly of the machine up the incline and is attached to an anchor jack located at the top of the incline. The safety cable 76 is also extended forwardly from the machine up the incline and is similarly anchored at the top of the incline. The low speed clutch 31 of the low speed drive is then applied to effect rotation of the feed drum 12 at the proper speed to wind in the feed cable, thereby to feed the machine up the incline at a cutting speed, moving the cutter bar along the coal face to make a cut along the base of the coal seam. As the feed drum is rotated, the safety drum 75 is concurrently rotated in a direction to wind in the safety cable 76, and since the safety cable tends to be wound in at a slightly higher rate than the feed cable, the safety cable is always automatically maintained taut under the control of the friction clutch, the latter slipping automatically when the safety cable is under sufficient tension. The friction clutch normally limits the traction exerted by the safety cable to a value less than sufficient to feed the machine up the incline. In the event of breakage of the feed cable or its release from its anchor, the safety cable 76 will automatically prevent movement of the machine down the incline, the pawl 93 of the ratchet mechanism automatically locking the safety drum against rotation in cable unwinding direction. When it is desired to lower the machine down the incline under the control of the safety drum, this may be accomplished by releasing the pawl (see Fig. 1) to permit rotation of the safety drum in cable unwinding direction, and the friction clutch at that time serves as a

frictional resistance means for braking drum rotation. Of course, during this braking operation the rotation of the shaft 65 is interrupted and the shaft is held against rotation by the worm gear 28, 29 of the drum driving means. By releasing the friction clutch 31 of the low speed drive and applying the high speed drive clutch 30, the feed and safety drums may be concurrently driven at a relatively high speed. When the friction clutch for the safety drum is fully loaded, the safety cable may be employed to feed the machine up the incline. Further, by properly adjusting the fulcrum of the lever 42 of the intermittent applying means for the low speed clutch 31, the safety drum may be intermittently driven concurrently with the feed drum in cable unwinding direction at any desired speed between the maximum low speed and zero.

As a result of this invention, it will be noted that an improved safety mechanism for a coal mining machine of the flexibility fed, floor cutter type adapted to operate on a steeply inclined coal seam, is provided whereby the possibility of undesired movement of the machine down a pitching coal seam is prevented. It will further be evident that by the provision of a safety drum which acts to wind in the safety cable at a rate slightly higher than the feed cable and under frictional control, the safety cable is always automatically maintained taut, thereby eliminating undesired slackness in the cables of previously known devices. Further, by the provision of a friction clutch which may serve as a brake, the machine may be lowered down the incline under the control of the safety drum. Other uses and advantages of the improved mining machine will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claim.

What I claim as new and desire to secure by Letters Patent is:

In combination, a machine body adapted to rest upon and slide over a mine floor, means for moving said body up an incline including a cable connectible at a point above and in advance of said body, a feed drum mounted to move with said body and coacting with said cable and means for rotating said feed drum in a direction to shorten the length of said cable in advance of said machine body, and means for precluding the sliding back of the machine in the event of sudden failure of said machine moving means including a safety cable also connectible at a point above and in advance of said body, a safety drum mounted to move with said body and of slightly larger effective diameter than said feed drum and coacting with said safety cable and means for rotating said safety drum at the same angular rate as said feed drum in a direction to shorten the length of said safety cable in advance of said machine body, said safety drum rotating means including a yielding connection set at a predetermined load for normally automatically limiting the traction exerted by said safety drum and cable to a value less than sufficient to move said body up the incline.

JOSEPH F. JOY.
